ATOMIZER

James Fletcher, Akron, Ohio, assignor to The Babcock & Wilcox Company, Rockleigh, N. J., a corporation of New Jersey

Application April 30, 1947, Serial No. 744,891

14 Claims. (Cl. 299—140)

1

The invention herein disclosed relates to the construction and operation of fluid dispersal apparatus adapted particularly for the dispersal of liquid fuel in the form of a spray presenting an extensive area of particle surface to an adjacent combustion supporting atmosphere.

An important feature of my invention is the provision of apparatus arranged for the atomization of liquids of various physical characteristics through the action of a suitable atomizing fluid such as air, steam, or other gaseous medium, such liquids including, especially, liquid fuels of the heavier grades and higher viscosities, such as heavy oil, tar and black liquor.

Another important feature is the provision of a particular form of spray wherein the normal expansion in cross section is maintained substantially greater in one direction than in a direction normal thereto.

More specifically, my invention has for an object the spraying of liquid from one or more outlet orifices in the form of a flat spray of generally oblong cross section throughout.

The various features of novelty which characterize my invention are pointed out with particularity in the claims annexed to and forming a part of this specification. For a better understanding of the invention, its operating advantages and specific objects attained by its use, reference should be had to the accompanying drawings and descriptive matter in which I have illustrated and described selected embodiments of my invention.

Of the drawings:

Fig. 1 is a longitudinal assembly view, in section, of an atomizer constructed in accordance with my invention;

Fig. 2 is an enlarged fragmentary section of Fig. 1 taken along line 2—2;

Fig. 3 is an end view of parts shown in Fig. 2;

Figs. 4 and 5 are transverse sections of Fig. 2, taken along lines 4—4 and 5—5, respectively, as viewed in opposite direction from a common plane;

Fig. 6 is a fragmentary longitudinal section of Fig. 2 taken along line 6—6;

Fig. 7 shows a modified form of sprayer plate as viewed from the fluid inlet side;

Figs. 8 and 9 are longitudinal sections of Fig. 7 taken along lines 8—8 and 9—9, respectively; and

Fig. 10 is similar to Fig. 7, showing the sprayer plate as viewed from the fluid outlet side.

As illustrated in Fig. 1, the atomizer assembly comprises a body member 12 at its outer end formed with fluid chambers or passages 13 and

2

14 therein and separably connected to a coupling member 15 providing inlet connections 16 and 17 for the separate admission of fluids to such passages. An outer tube or barrel 18 and an inner tube 19, coaxially arranged and each connected at one end to body member 12, provide an outer annular fluid supply passage 21 in communication with body passage 13 and a centrally disposed fluid supply passage 23 in communication with body passage 14.

A sprayer head or nozzle 24 is secured at one end to the inner end of tube 19 as by threads 25 and at its opposite end is formed with a flange 26 seated within a counterbore 27 at the inner end of atomizer barrel 18, and providing a planar joint surface 28 against which a sprayer plate 29 is assembled. The nozzle 24 is formed with a central passage or bore 31 in direct communication with the central fluid supply passage 23 and in its outer end surface 28 is formed with an annular recess or groove 32 having communication with the annular fluid supply passage 21 through a series of circumferentially spaced holes 34 extending from the base of the recess through flange 26. Fluid admitted through inlet 16 is thus conducted to the sprayer plate 29 at joint surface 28 through body passage 14, central inner tube passage 23, and nozzle bore 31, while fluid admitted through inlet 17 is conducted through body passage 13, annular barrel passage 21, circumferentially spaced holes 34 and annular recess 32.

The sprayer plate 29, as shown, is of one-piece construction having a rearward base surface 35 of which the major portion is of annular formation in a plane normal to the central longitudinal axis of the atomizer assembly, the plate surface 35 being maintained in fluid tight contact with the nozzle end surface 28 by means of a cap 36 having an inturned flange portion 37 engaging a circumferential base flange portion 38 of the plate and secured to the barrel tube 18 as by threads 39. The assembly of outer and inner tubes 18 and 19 and of other parts thus far described is enclosed by an outer tube 41 having one end connected to the coupling ring 42 by threads 43, the tube 41, known as a distance piece, serving as a shield for the assembly and as an atomizer supporting member.

The sprayer plate 29 is formed with a single discharge orifice 45 providing a substantially flat spray of oblong cross section in planes normal to the axis of fluid discharge, the orifice or port 45 being in the form of a diametrically arranged slot having parallel side walls 46 joined at their

ends by arcuate surfaces 47. The forward end surface 48 of plate 29 is formed as a surface of revolution about the central axis of the plate and tubular atomizer assembly, the surface 48 including a major conical portion 49 having side wall portions inclined to the central axis at an angle of about 45° and thereby defining an included angle of about 90°, the surface 48 terminating in a spherical tip portion 51 determining a total axial dimension of sprayer plate generally less than its maximum diameter at its base.

Referring to Figs. 2 and 3 in particular, the outwardly curved end walls 47 include inner end portions 52 arranged normal to base surface 35 and thus parallel to each other and to the central axis for a portion of the distance through plate 29, the outer end portions 53 of such walls diverging from the central axis and from each other and terminating in substantially right angled relation to the conical forward surface portion 49 of the plate, the end wall surface portions 52 and 53 being joined by a rounded transition surface 54 of suitable radius. The entrance to slot 45 is enlarged to the diameter of the nozzle bore 31 by means of a conical surface 56 which extends from the plane of base surface 35 at an angle of about 45° and intersects each side and end wall of the slot in a curved line 57. Fluid inlet ports 58, having circumferentially spaced inlet openings 59 in the annular portion of base 35, extend at an inclination to the base to intersect the side and end walls of slot 45 in two groups of outlet openings 61 discharging into the slot from opposite directions. The ports 58 are arranged in groups at opposite sides of the central longitudinal plane A—A of slot 45, with the ports of each group inclined at an angle of about 45° to plane A—A, and with the longitudinal axis of each port in a plane normal to plane A—A. The ports 58 thus have their longitudinal axes in parallel planes although, as will be noted from Fig. 5, the longitudinal axis planes of ports 58 at one side of slot plane A—A are displaced from the longitudinal axis planes of ports 58 at the opposite side, thereby providing outlet openings 61 in displaced alternating relation at opposite sides of slot 45 to afford a substantially continuous area of fluid admission through ports 58 throughout the elongated cross sectional dimension of the slot. Each port 58 is of circular cross section, and of substantially uniform cross sectional area, throughout its axial extent, and may therefore be conveniently formed in the plate by drilling.

In view of the particular pattern of spray provided, it is desirable to maintain the sprayer plate 29 in predetermined angular relation to such parts of the atomizer assembly as are normally installed so as to be held in a fixed angular position. For this purpose, one or more dowels 62 may be employed, extending from nozzle 24 into a socket or sockets 63 in sprayer plate 29, and thereby providing a positive indexing or keying means whereby the sprayer plate may be repeatedly assembled into the same angular position to maintain a predetermined angular position for the spray axis A—A. In the arrangement shown, it may be assumed that the dowels 62 and nozzle passages 34 are circumferentially arranged so as to maintain the spray axis A—A in a horizontal position, or at least parallel to a horizontal line. It will be understood, however, that the circumferential arrangement of such dowels and passages may be altered to provide other angular positions of the spray axis as

might be determined by the particular environment of operation.

Figs. 7-9 show a modified form of sprayer plate 71 also providing a generally flat fan-shaped pattern of spray, and adapted for incorporation in an atomizer assembly such as is illustrated in Fig. 1. Plate 71 is of substantially the same proportions as plate 29 whereby the total axial dimension of plate 71 is generally less than the maximum plate diameter at its base. In this embodiment of the invention, the total fluid discharge area is provided by separate outlet ports 72 having their longitudinal axes in a common diametral plane as indicated by the section taken along line 8—8 of Fig. 7. Ports 72 are arranged in diverging relation with respect to each other and, in the arrangement shown, are formed about axes diverging from a common point on the central longitudinal axis of the circular plate, one port of the series being centrally disposed and in alignment with the central axis. The ports 72 extend entirely through the plate from a row of inlet openings 73 in the rearward plate surface 74, to a row of outlet openings 75 in the forward plate surface 76, each port 72 having its outlet end portion 78 of greater diameter than its inlet end portion 79 for reasons which are later made apparent. As shown, the rearward surface 74 comprises an outer annular surface portion 81 arranged in a plane normal to the central axis, together with a centrally disposed inner surface portion 82 in which are formed the inlet openings 73, the central portion 82 being formed as a recess having an end wall 83 parallel to the base surface portion 81, and a conical side wall portion 84 defining an included angle usually less than 90°.

The ports 72 extend at right angles to the forward plate surface 76 which is approximately spherical in contour, being formed of successive conical portions 85 and 86 arranged annularly of a centrally disposed planar portion 87 parallel to the central recess surface 81. The ports or holes 72 may thus be readily drilled from the forward surface 76 and, being of circular cross section, provide discharge openings 75 having substantially circular rims contributing to substantial uniformity of jet discharge from all ports.

A second series of holes or ports 89, suitably of circular cross section and having circumferentially spaced inlet openings 91 in the annular base surface 81, extend partially through plate 71 to form junctures with ports 72 at their enlarged outlet ends 78, closely adjacent the base portions thereof. Ports 89 are symmetrically arranged in circumferentially spaced groups, one group at each side of the row of ports 72, with the longitudinal axes of ports 89 in parallel planes normal to the plane of the row of ports 72, and with the longitudinal axes of ports 89 of each group parallel to each other and arranged at substantially equal inclinations to the plane of ports 72, the angle of inclination being suitably of the order of about 30 to 45 degrees. In the arrangement shown, each port 72 is thus intersected by two ports 89 entering from opposite sides and having their longitudinal axes in a common plane to intersect in a point on the center line of a port 72 within its enlarged outlet end 78.

When sprayer plate 71 is substituted for sprayer plate 29 in an assembly such as is indicated in Fig. 1, the dowels 62 are omitted and the correct angular position of the plate deter-

mined by inspection, the clamping effect of cap 36 being relied upon to maintain the sprayer plate in the desired assembled relation to the remainder of the assembly; otherwise dowels 62 and dowel sockets 63 may be included as in Fig. 1, as will be understood.

The sprayer plates thus described are adapted for spraying liquids of various grades and viscosities as previously indicated, including for example such liquid fuels as oil, tar, sludge and the concentrated liquors resulting from various pulping processes. When used for spraying liquid fuels, the particular pattern of spray is often a distinct advantage in heat recovery units where the more conventional conical pattern of spray would not be suitable. In certain installations, while the character of fuel may be one controlling factor, it may also be necessary to adopt the flat fan-shaped pattern to provide the desired relation to an existing or contemplated source of combustion air, or to other fuel firing apparatus using gas, coal, oil, or other fuel.

The form of sprayer plate 29 makes it particularly adaptable for spraying residual liquor, mainly because of the provision of a single fuel port 45 in which the total required fuel flow area is continuous and centrally disposed, and in axial communication with fuel supply passage 23, whereby plugging with this type of fuel is obviated. The residual or black liquor is thus admitted through inlet 16 and passes from the central atomizer passage 23 direct to the diametral sprayer plate port 45. The gaseous atomizing fluid, suitably steam, is admitted through inlet 17 and passes from the annular passage 21 to the groups of sprayer plate ports 58 for discharge into port 45 in oblique relation to the fuel stream flowing therethrough. Such confluence or junction of the atomizing fluid streams with the stream of fuel results in atomization of the liquid fuel, and since the mixing occurs within the body of the plate, the atomized fuel is discharged as a flat fan-shaped spray as determined by the arrangement of slot walls 46 and 47.

Sprayer plate 71 is of a form particularly adapted for use with liquid fuels less likely to cause plugging of the passages. In this form, the inlets 16 and 17 may, as a general rule, be used interchangeably for the fuel and the fuel atomizing medium. Assuming, for example, that fuel oil is admitted through inlet 16, and steam through inlet 17, then the fuel is directed through sprayer plate ports 72 and the fuel atomizing medium through opposing groups of ports 89, the resulting atomized fuel being discharged in a series of jets through the row of outlet openings 75 to provide a flat fan-shaped form of spray.

While in accordance with the provisions of the statutes I have illustrated and described herein the best form of my invention now known to me, those skilled in the art will understand that changes may be made in the form of the apparatus disclosed without departing from the spirit of the invention covered by my claims, and that certain features of my invention may sometimes be used to advantage without a corresponding use of other features.

I claim:

1. Apparatus for spraying liquid in a fan-shaped pattern comprising a sprayer plate having a rearward and a forward surface transversely arranged relative to a common rectilinear axis, means defining a fluid directing path through said plate from one of said surfaces to the other, said path being of symmetrical formation rela-

tive to a median plane containing said axis and providing a total flow area throughout of greater dimension in said median plane than in a plane normal thereto, said plate having fluid inlet ports extending partially therethrough from said rearward surface and individually forming junctures with said fluid directing path, said ports being arranged in spaced groups respectively at opposite sides of said median plane and being cylindrically formed throughout about straight-line axes parallel to said normal plane, each port of each of said groups opening into said fluid directing path intermediate opposite ends of said path and at an acute angle relative to said median plane.

2. Apparatus for spraying liquid in a fan-shaped pattern comprising a sprayer plate having its body portion of circular formation about a central axis and having a rearward and a forward surface arranged transversely of said axis, said plate having a liquid conducting path extending therethrough from said rearward to said forward surface, said path having its inlet in a central portion of said rearward surface to which said liquid is supplied throughout the entire area of said inlet, said path providing a total flow area throughout of greater dimension in a median plane containing said axis than in a direction normal to said plane, said flow area throughout said path being diametrically distributed in symmetrical relation to said axis and terminating at said forward surface at greater distances from said axis than at said rearward surface, said plate having ports extending partially therethrough from an annular portion of said rearward surface and individually forming junctures with different portions of said liquid conducting path at points rearwardly spaced from said forward surface, said ports being arranged in spaced groups respectively at opposite sides of said plane and in the respective groups being formed throughout about parallel straight-line axes inclined toward said median plane in the direction of said forward surface.

3. A sprayer plate having a body portion of symmetrical formation about a central axis and arranged to discharge liquid received therein in the form of a flat spray having its major axis of cross section in a plane containing said axis, said plate having a port extending therethrough from a rearward to a forward surface thereof and throughout its axial extent providing a fluid flow area elongated in a direction paralleling said plane, said port providing an entrance area in said rearward surface for receiving an atomizable liquid and providing an outlet area in said forward surface for discharging said liquid in said flat form of spray, said plate being formed with ports arranged in spaced groups respectively at opposite sides of said plane and providing circumferentially spaced inlet areas in said rearward surface for admission of a gaseous atomizing medium thereto, said last named ports extending partially through said plate and individually terminating in junctures with said first named port at points inwardly spaced from both said surfaces, said last named ports being formed throughout about straight-line axes disposed in parallel planes arranged at right angles to said first named plane.

4. A sprayer plate having a body portion of circular formation about a central axis and arranged to discharge liquid received therein in the form of a flat spray having its major axis of cross section in a diametrical plane, said plate having

a parallel-sided port extending therethrough from a rearward to a forward surface thereof and throughout its axial extent providing a fluid flow path of oblong cross section having its major axis continuously in said plane, said port having its inlet in said rearward surface for receiving said liquid and having its outlet in said forward surface for discharging said liquid in said flat form of spray, said plate being formed with ports arranged in groups at opposite sides of said plane and having inlets in said rearward surface for admission of a gaseous atomizing medium thereto, said last named ports extending partially through said plate and individually terminating in spaced relation to both said surfaces in junctures with said liquid receiving port, said last named ports in each of said groups being formed throughout about parallel straight-line axes inclined toward said diametral plane in the direction of said forward surface, said last named ports in the respective groups having outlets in opposite sides of said parallel-sided port at interspersed positions paralleling said major axis.

15. A sprayer plate of one-piece construction having one or more ports extending therethrough and constituting a fluid flow path adapted to receive liquid fuel at one end and to discharge said fuel in a flat form of spray from its opposite end, said path having its flow area substantially evenly distributed with respect to a median plane of flow and also with respect to a plane normal thereto, said flow path from one end thereof to the other providing a flow area more widely distributed in a direction parallel to said median plane than in a direction normal thereto, said flow area increasing toward said discharge end to a maximum at said end, said plate having ports extending in continuous lengths from said one end of said plate to said fluid flow path and arranged to direct a fluid atomizing medium into said path at locations of increased flow area inwardly spaced from both said surfaces, said last named ports respectively forming continuous straight-line passages of circular cross-section throughout and entering said path at acute angles from opposite sides of said median plane.

16. A sprayer plate having a port extending therethrough and constituting a fluid flow path adapted to receive an atomizable fuel at one end and to discharge said fuel in an atomized state from its opposite end, said port having parallel side walls at opposite sides of a median plane and having opposing end walls symmetrically arranged with respect to a central axis in said plane, said end walls parallelizing said axis adjacent said fuel-receiving end and diverging from said axis toward said fuel-discharging end, said plate having ports extending partially therethrough from an exterior surface thereof and arranged to direct a fluid atomizing medium into said path from opposite sides of said median plane, said last named ports respectively forming continuous straight-line passages of circular cross-section entering said path at substantially equal inclinations to said median plane at locations rearwardly displaced from the discharge end of said path.

17. A sprayer plate of one-piece construction having a port extending therethrough and forming a transversely continuous flow path of oblong cross section having its major axis in a median plane, said port having an inlet for liquid fuel in a rearward exterior surface of said plate and having an outlet for atomized fuel in a forward exterior surface thereof, said port having parallel side walls equidistant from said median

plane throughout the length of said port and having opposing end walls symmetrically arranged with respect to a central axis in said plane, said forward surface being convexedly formed as a surface of revolution about said axis, said end walls including portions diverging from said axis toward said forward surface and terminating thereat in substantially normal relation thereto, said plate having ports extending partially therethrough from said rearward surface and individually terminating at said side walls in junctures with said first named port at opposite sides of said median plane, said junctures being located between said surfaces at substantially the base of said diverging end wall portions, said plate being solid throughout except for the spaces occupied by said ports.

18. A sprayer plate having a first series of ports extending therethrough and constituting a fluid flow path adapted to receive liquid at one end and to discharge said liquid in an atomized state from its opposite end, said ports having longitudinal axes arranged in diverging relation to each other in a common plane to provide a fan-shaped spray, said plate having a second series of ports extending partially therethrough and arranged to discharge a fluid atomizing medium into ports of said first series, said ports of said second series being arranged at opposite sides of said common plane and having longitudinal axes disposed in planes normal to said common plane.

19. A sprayer plate having a first series of ports extending therethrough and constituting a fluid flow path adapted to receive liquid at one end and to discharge said liquid in an atomized state from its opposite end, said ports having longitudinal axes arranged in diverging relation to each other in a common plane to provide a fan-shaped spray, said ports being of cylindrical formation throughout and each having its outlet end portion adjacent a forward plate surface of greater cross section than its inlet end portion adjacent a rearward plate surface, said plate having a second series of ports extending partially therethrough from said rearward surface and arranged to discharge a fluid atomizing medium into ports of said first series, said ports of said second series being arranged at opposite sides of said common plane and entering each port of said first series in pairs, said ports forming each of said pairs entering a port of said first series adjacent the base of said portion of greater cross section.

20. An atomizer having an assembly of concentrically arranged inner and outer tubular members normally fixed against rotation about a common central axis and providing a central and an annular fluid supply area for a liquid fuel and a fuel-atomizing fluid respectively, a sprayer plate removably joined to said assembly in axial relation thereto and having a first and a second fluid flow path arranged to separately receive said fuel and said fuel-atomizing fluid from said areas, said plate being of generally circular formation about said axis and of smaller dimension longitudinally of said axis than in a direction normal thereto, said first path extending entirely through said plate and providing a flow area of diametrically elongated cross section throughout, said first path having an inlet end portion receiving said liquid fuel throughout its total elongated cross section and having a connecting outlet end portion from which said fuel is discharged in a flat spray substantially

in the plane of said axis, said second path being formed of circumferentially spaced groups of ports restricted to regions at opposite sides of said plane and directing said fuel atomizing fluid into said liquid fuel receiving portion of said first path, said ports forming continuous straight-line passages each having its inlet in an exterior surface of said plate and its outlet in a wall of said first fluid flow path.

11. An atomizer as defined in claim 10 and further comprising keying means disposed between said groups of ports and engaging said sprayer plate and said tubular assembly for positively indexing said sprayer plate in a predetermined angular position.

12. Apparatus for effecting mixture of fluids delivered thereto and for discharging the resulting mixture in a fan-shaped pattern, said apparatus comprising a fluid discharge plate having a rearward and a forward surface transversely arranged relative to a common rectilinear axis, means defining a fluid directing path extending through said plate from one of said surfaces to the other, said path being of symmetrical formation relative to a median plane containing said axis and providing a total flow area throughout of greater dimension in said median plane than in a plane normal thereto, said flow area increasing toward said forward surface to a maximum at said surface, said plate having fluid inlet ports extending partially therethrough from said rearward surface and individually forming junctures with said fluid directing path at locations of increased flow area inwardly spaced from both said surfaces, said ports being arranged in spaced groups respectively at opposite sides of said median plane and being cylindrically formed throughout about straight-line axes parallel to said normal plane, each port of each of said groups opening into said fluid directing path intermediate opposite ends of said path and at an acute angle relative to said median plane.

13. A sprayer plate having a first series of ports extending therethrough from a rearward surface thereof and having a second series of ports extending partially therethrough from said surface and forming junctures with ports of said first series within the body of said plate, said ports of the respective series having separate in-

10

lets in said rearward surface for an atomizable liquid and an atomizing fluid respectively whereby a mixture of said liquid and said fluid is provided at each of said junctures, said ports of said first series having longitudinal axes arranged in forwardly diverging relation to each other substantially in a common plane for discharging the total mixture of liquid and fluid from said junctures in a fan-shaped spray, said ports of said second series being arranged at opposite sides of said common plane and having longitudinal axes disposed in planes substantially normal to said common plane.

14. A sprayer plate having a first series of ports extending therethrough and constituting a fluid flow path adapted to receive liquid at one end and to discharge said liquid in an atomized state from its opposite end, said ports having longitudinal axes arranged in diverging relation to each other in a common plane to provide a fan-shaped spray, said ports being of cylindrical formation throughout and each having its outlet end portion adjacent a forward plate surface of greater cross section than its inlet end portion adjacent a rearward plate surface, said plate having a second series of ports extending partially therethrough from said rearward surface and arranged to discharge a fluid atomizing medium into ports of said first series, said ports of said second series being arranged at opposite sides of said common plane and each entering a port of said first series adjacent the base of said portion of greater cross section.
